[57] CLAIM

The ornamental design for an animal leash, as shown and described.

DESCRIPTION

FIG. 1 is a top left perspective view of a first embodiment of an animal leash showing my new design;
 FIG. 2 is a top view thereof, the bottom view being a mirror image thereof;
 FIG. 3 is a right side view thereof, the left side being a mirror image thereof;
 FIG. 4 is a front view thereof;
 FIG. 5 is a rear view thereof;
 FIG. 6 is a perspective view of an alternate embodiment of FIG. 1; and,
 FIG. 7 is a perspective view of a second alternate embodiment of FIG. 1; wherein the difference between the embodiments is the valleys formed in the lead.
 The broken line drawing of the snap hook and indicia in FIGS. 1-3 and 6-7 is for illustrative purposes only and forms no part of the claimed design. The animal leash is shown as broken away in FIGS. 1, 2, 3, 6 and 7 to indicate indeterminate length.
